UNITED STATES PATENT OFFICE.

THORN COPEMAN, OF EDGAR MILLS, CANADA, ASSIGNOR OF ONE-THIRD TO
JOSEPH WAITE, OF SAME PLACE.

RAILWAY-SWITCH.

SPECIFICATION forming part of Letters Patent No. 656,691, dated August 28, 1900.

Application filed June 9, 1900. Serial No. 19,695. (No model.)

To all whom it may concern:

Be it known that I, THORN COPEMAN, a citizen of Canada, residing at Edgar Mills, in the county of Essex and Province of Ontario, 5 Canada, have invented certain new and useful Improvements in Railway-Switches, of which the following is a specification.

This invention relates to that kind of railway-switch in which there are vertically- 10 movable switch-point rails, one being depressed while the other is at the level of the rails; and the invention consists in the peculiar and novel means for operating such switch-point rails by supporting the same 15 upon cam-rollers in the manner more fully hereinafter described, and shown in the accompanying drawings, in which—

Figure 1 is a plan of the switch. Fig. 2 is a cross-section thereof on line *x* *x*, Fig. 1. 20 Fig. 3 is a cross-section on line *y* *y*, Fig. 1. Fig. 4 is a plan of one of the switch-points with the housing-plate shown in dotted outlines. Fig. 5 is an elevation of Fig. 4. Fig. 6 is a detached perspective view of one of the 25 switch-points.

A represents the stationary rails of the main track.

B represents the stationary rails of the siding.

30 *C* *C* are the two movable switch-point rails in line with the inner rails.

D *D* are cam-rollers, one beneath each switch-point rail and supporting the same in position upon the ties. Each cam-roller is 35 substantially coextensive with the switch-point rail and is composed of a roller portion *a* and a cam portion *b*. Each cam-roller bears with its roller portion against the under side of the switch-point rail and is held in position thereon by straps *c* or in any other suitable way which permits the roller to be revolved. Preferably the under side of the switch-point rail is made to fit the top of the roller and to provide a wide bearing the whole 45 length. The cam-roller is placed at a slight angle to the switch-point rail, as shown in Fig. 4, and a rib *d* is formed on the inside at the pointed end of the switch-point rail. Each cam-roller is confined in position at its 50 outer side by a suitable filler-block *e*, secured to the outer rail, and by a housing-plate *E*

on the inner side, the two forming together a vertical guideway for the switch-point rail.

The housing-plate *E* is formed on the inside with a rib *f*, which is adapted to bear 55 against the adjacent face of the cam portion of the roller, as will be more fully hereinafter described. The ends of the housing-plate are secured by bolts *g* *g* to the stationary rails, the bolts *g* passing through elongated slots 60 in the housing to permit expansion to take place without binding the switch-point rail and its supporting cam-roller.

The cam-rollers are supported upon ties, suitable bearing-plates *h* being used, and each 65 cam-roller is provided with a crank-arm *F*, connected in any suitable manner with the switch-operating rod *G*.

In practice the parts being constructed and arranged as shown and described they are 70 intended to operate as follows: In the position of the switch as shown in Fig. 2 the switch-point rails are supported by the cam-rollers at the relative heights required to keep the main track open. If the switch is 75 thrown in the opposite direction, the cam-rollers will be revolved one-quarter of a revolution, thereby causing a reversal of the positions of the switch-point rails which connect the switch with the main track. 80

In revolving the cam-rollers it will be seen that the ribs *f* of the housing act as a fulcrum for the cam-rollers, and thereby give an advantage in the application of power in throwing the switch. 85

My construction has the great advantage that the cam-rollers provide a continuous solid support and bearing for the switch-point rails and also it is not liable to get out of order or become inoperative by reason of snow 90 or ice or by being maliciously tampered with.

What I claim as my invention, and desire to secure by Letters Patent, is—

1. In a railway-switch, the combination with the stationary rails of a main line and 95 siding, of vertically-movable switch-point rails held in vertical guide-bearings in line with the inner rails at their junction with the outer rails, cam-rollers interposed between the same and the ties in alternate positions 100 to support said switch-point rails, one at the level of the stationary rails and one below,

and means for simultaneously revolving said cam-rollers, each cam-roller being coextensive with the switch-point rail and seated against a continuous bearing formed on the 5 under side of the switch-point rail free to be revolved on said bearing from one position into an alternate position.

2. In a railway-switch, the combination with the stationary rails of a main line and 10 siding, of vertically-movable switch-point rails held in vertical guide-bearings in line with the inner rails at their junction with the outer rails, cam-rollers interposed between the same and the ties and forming continuous 15 bearing or seat for the switch-point rails, one beneath one switch-point rail in position to support the same at the level of the stationary rails and the other in alternate position beneath the other switch-point rail and 20 supporting the same at a lower level, each cam-roller having a circular roller portion and each switch-point rail having a continuous seat formed on the under side for said roller portion on which the cam-roller is 25 adapted to be rotated, both cam-rollers being connected for simultaneous operation by the switch-rod.

3. In a railway-switch, the combination with the stationary rails of a main line and 30 siding, of the vertically-movable switch-point rails C, held in vertical guide-bearings in line with the inner rails, one at the level of the

stationary rails and one at a lower level, the cam-rollers D eccentrically journaled to the under side of said switch-point rails and supporting the same directly upon the ties, in alternate positions of said cam-rollers, the arms F on the cam-rollers connected to the switch-operating rod, and the housing-plates E having the ribs f adapted to operate as a 40 fulcrum for the cam-rollers, all substantially as described.

4. In a railway-switch, the combination with the stationary rails A, B, of the vertically-movable switch-point rails C, the cam-rollers D upon which said switch-point rails are mounted free to rotate said cam-rollers to support the switch-point rails upon the ties in alternate positions of said cam-rollers, one level with the stationary rails and the other 50 below said level, the arms F on said cam-rollers, the switch-rod to which they are connected, and the housings E provided with the ribs f, the aforesaid cam-rollers composed of the roller portions a and cam portions b forming between them a longitudinal groove into which said ribs f project to operate as a 55 fulcrum in rotating the cam-rollers.

In testimony whereof I affix my signature in presence of two witnesses.

THORN COPEMAN.
